[57] CLAIM

The ornamental design for a bottle, as shown and described.

DESCRIPTION

FIG. 1 is an elevational view of a bottle showing my new design, the opposite side being substantially the same in appearance;

FIG. 2 is a cross sectional view taken on the line 2—2 of FIG. 1;

FIG. 3 is a view similar to FIG. 1 with the bottle rotated slightly in a counterclockwise direction;

FIG. 4 is an elevational view looking from the right of FIG. 1, the opposite side being substantially the same in appearance; and

FIG. 5 is a view similar to FIG. 4 with the bottle rotated slightly in a counterclockwise direction.

FIG. 1

FIG. 2

FIG. 3

FIG. 4

FIG. 5
